UNITED STATES PATENT OFFICE.

FRA NCIS WINDHAM, OF LONDON, ENGLAND.

SAFETY-RAZOR.

1,104,857.

Specification of Letters Patent. Patented July 28, 1914.

Application filed April 10, 1913. Serial No. 760,331.

To all whom it may concern:

Be it known that I, FRANCIS WINDHAM, subject of the King of England, residing at London, in England, have invented certain new and useful Improvements in Safety-Razors, of which the following is a specification.

This invention relates to safety razors and has for its object to provide an improved frame or holder capable of being used with blades of the rigid single edged type or with thin double edged blades with or without perforations therein.

A further object of this invention is to provide a frame or holder of cheap construction which will permit of the blade being readily inserted, removed or adjusted, the dimensions of the frame and its construction being such that the complete razor can be readily carried in the pocket if desired without fear of danger or damage to the blade.

According to this invention the blade is held in the operative position solely by a spring clip which grips the blade between the longitudinal edges of the latter and also constitutes the frame or holder, and means are connected to the clip enabling it to be opened to release the blade. The comb or guard may be formed in one with the clip or gripped in place thereby in a manner similar to the blade. In a preferred construction the longitudinal edges of the clip, which is preferably formed of spring steel of approximately the same width as the blade, have handles pivoted thereto which constitute the means for opening the clip, one of these members serving as the operating handle for the razor when in use, the other member, when folded into the same plane as the blade, also serving as a guard to protect the blade when not in use. The handles are preferably conveniently formed of wire and in the preferred construction the clip is of substantially U or loop section, the lower limb thereof being extended so that its longitudinal edge projects a suitable distance beyond that of the upper portion of the clip. This extended portion of the clip may be perforated or otherwise formed into a comb or guard when this is integral with the clip, or the extension may serve as a support for the teeth of a separate comb which is gripped in place between the two longitudinal edges of the clip, a projection or the like being preferably struck up from the under portion of the clip

to give the necessary inclination to the comb or to the blade which it supports. Where the comb is integral with the clip one or more such projections may be provided to impart the necessary angle to the blade.

In operation the handle or lever pivoted to the under portion of the clip, which is preferably longer than that carried by the other edge of the clip, is set at substantially right angles to the blade the other shorter handle being turned back so as to leave the cutting edge of the blade free. If the blade is to be removed, inserted or adjusted both handles are bent back in which position they constitute levers to open the clip and when the razor is not in use, the two handles are folded forward so as to occupy a plane parallel to the blade in which position they serve to protect the latter from damage or from coming into contact with say the pocket or case in which the razor may be carried.

In the accompanying drawings which show two forms of razor frames or holders in accordance with this invention, Figure 1 is a plan of a holder for a double edged perforated blade. Fig. 2 is an inverted plan thereof. Fig. 3 is a central vertical section showing the handles in the operative position. Fig. 4 is a perspective view of the clip member and pivoted handles. Fig. 5 is a plan of a modified form of holder in which the comb is integral with the clip, a rigid blade being shown in position, and Fig. 6 is a central vertical section through this construction, the handles being in their operative position.

In the construction shown in Figs. 1-4, the holder comprises a clip formed of a single piece of spring strip metal which is bent in the form of a loop or U, the lower limb A of the clip being prolonged so as to project beyond the longitudinal edge of the upper member A' thereof. The longitudinal edges of the lower and upper members of the spring clip are bent over to form tubular loops or sockets B B' respectively, into which are sprung the ends of bent wire levers C C', the longer lever C being thus pivoted to the projecting edge of the lower limb A of the clip, while the shorter handle is similarly connected to the longitudinal edge of the upper member A'. Slots B² are formed at the ends of the tubular sockets B for the operating handle C, the handle springing into these slots and being thus held in the operative position shown

in Fig. 4 when it is turned into this position. Struck up from the under portion of the clip A is a lug or tongue A² which forms a stop to support the comb D which comprises a plate having teeth D' formed along its outer edge. Raised bosses D² are also struck up or otherwise formed on the upper surface of the comb plate D which are adapted to engage corresponding perforations 10 provided in the usual manner in the blade E which in the example illustrated is of the known flexible double edged type. When the razor is to be used, the position of the comb and the blade it carries relatively to 15 the clip is adjusted to suit the user's requirements the two pivoted levers C C' being folded back as far as they will go and then pressed together so as to release the gripping edges of the clip and enable this adjustment to be made. The levers C C' are then made to assume the position shown in 20 Fig. 3 in which position the longer lever C constitutes the operating handle. The blade and the comb are instantly released on bringing the outer ends of the two levers together again and it will thus be seen that the blade and comb can readily be removed 25 for cleaning and drying purposes. If it is desired to carry the razor and its blade in 30 the pocket this may be done without danger by folding over the handles or levers C C' in the position shown in Figs. 1 and 2 in which position the blade is protected by the shorter handle C' which lies in the plane 35 approximately parallel to the longer handle C and the cutting edge of the blade E.

In the modification shown in Figs. 5 and 40 6 the comb plate is unnecessary since a series of perforations F are formed in the extended edge of the under member A of the clip, the guard or comb being thus formed. In this instance in place of a single central stop or projection A² two of such stops A³ are conveniently struck 45 up from the under member A, these projections engaging the under surface of a rigid blade G of wedge-shaped cross-section. In this case if desired stops (not shown) may be formed at the extremities of the comb to limit the downward 50 movement of the cutting edge of the blade if such are found necessary though as will be seen from the drawings the blade is gripped in the same manner as in the construction already illustrated, that is to say

the clip grips the blade between the longitudinal edges of the latter thus obviating the necessity for any fixed or adjustable tension member bearing upon the upper longitudinal edge of the plate. The pivoted handles or levers C C' are similar in form and operation to those already described with reference to the arrangement shown in Figs. 1-4.

It will be appreciated that the drawings show two constructions only by way of example and that various modifications may be made without departing from this invention.

What I claim as my invention and desire to secure by Letters Patent is:—

1. In a safety razor the combination of a spring clip of substantially U or loop section adapted to grip a blade between its longitudinal edges, means for supporting a blade within said clip, a comb or guard for the cutting edge of said blade and levers pivoted to the longitudinal edges of the clip and constituting means for opening the clip and guarding the exposed edge of the blade when the razor is not in use, and serving as a handle for operating the razor.

2. In a safety razor, the combination of a spring clip of substantially U or loop section, a comb gripped in place between the longitudinal edges of the clip and serving as a support for a blade which is held in its operative position by the same clip and levers pivoted to the longitudinal edges of the clip and constituting means for opening the clip and guarding the blade when the razor is not in use, and serving as a handle for operating the razor.

3. In a safety razor, the combination of a spring clip of substantially U or loop section, a comb gripped in place between the longitudinal edges of the clip, a double-edged blade removably mounted on the comb and held by the same clip in its operative position so as to expose one cutting edge, and levers pivoted to the longitudinal edges of the clip and constituting means for opening the clip and guarding the exposed edge of the blade when the razor is not in use, and serving as a handle for operating the razor.

Dated this 28th day of March 1913.
F. WINDHAM.
